FISHING REEL

David A. Bellinger, South Burnaby, British Columbia, Canada

Application November 2, 1953, Serial No. 27,412

Term of patent 7 years

(Cl. D31—4)

To all whom it may concern:

Be it known that I, David A. Bellinger, a citizen of Canada and a resident of the municipality of South Burnaby, in the Providence of British Columbia, Canada, have invented a new, original, and ornamental Design for a Fishing Reel, of which the following is a specification, reference being had to the accompanying drawing, forming a part thereof.

I claim:

The ornamental design for a fishing reel, as shown and described.
